UNITED STATES PATENT OFFICE.

CLARE H. DRAPER, OF HOPEDALE, MASSACHUSETTS. ASSIGNOR TO DRAPER COMPANY, OF HOPEDALE, MASSACHUSETTS, A CORPORATION OF MAINE.

FILLING-REPLENISHING LOOM.

No. 881,063.

Specification of Letters Patent.

Patented March 3, 1908.

Application filed April 29, 1907. Serial No. 370,747.

To all whom it may concern:

Be it known that I, CLARE H. DRAPER, a citizen of the United States, residing in Hopedale, county of Worcester, and State of Massachusetts, have invented an Improvement in Filling-Replenishing Loom, of which the following description, in connection with the accompanying drawing, is a specification, like letters on the drawing representing like parts.

10 This invention relates to looms provided with mechanism to replenish automatically the running filling and having means to detect filling absence on each pick, and arranged to arrest the operation of the take-up mechanism on each detection of filling absence.

My invention comprehends various features of operation found in such looms, and 20 is embodied in a so-called "feeler" loom, wherein by or through filling-exhaustion indicating mechanism filling replenishment is effected prior to complete exhaustion of the supply of filling in the active shuttle.

25 In United States Patent No. 833,796 granted to Northrop October 23, 1906, a loom is shown and described provided with a feeler and two filling-detectors, and so arranged that by a change in the position, and 30 resulting operation, of a controlling or governing member the loom may be operated in a variety of ways.

35 My present invention relates to such a loom, and it also embodies a controlling or governing member adapted to be changed to vary the operation of the loom, the objects of the invention being a simplification of construction and arrangement in various particulars, and the obviation of some features 40 which are found in practice to be attended with certain disadvantages.

The various modes of operation of the loom embodying my present invention may be classified in a manner similar to that 45 adopted in the Northrop patent referred to, as follows:

50 A. Operating as an ordinary feeler-loom, the feeler and the main or left-hand filling-detector arranged to effect filling replenishment, the feeler acting prior to complete exhaustion of the running filling and the said detector acting when filling absence is detected thereby, both the main and the auxiliary, or right-hand filling-detector controlling the take-up.

B. Operating with the feeler mechanism inoperative, but with the two filling-detectors operating as in (A.). Conversion from A to B involves merely retaining the feeler mechanism inoperative.

60 C. Operating with the feeler mechanism operative, but with the two filling-detectors acting to effect stoppage of the loom upon detection of filling absence, and to arrest take-up upon such detection. The conversion of the loom to operate in this case is effected by a change in the controlling or governing member, as will be explained.

D. By rendering the feeler inoperative when the loom is otherwise set to operate as 70 in case C, so that the loom operates as a common double-fork loom, take-up being arrested and loom stoppage effected when the filling runs out or breaks.

75 The filling-exhaustion-indicating mechanism herein shown is substantially the same as shown in the Northrop patent referred to, and the double-detector devices are in the main such as shown in that patent, such differences as may exist in the structure forming 80 the subject-matter of this invention being referred to hereinafter.

85 The various novel features of my invention, in construction, arrangement and operation will be fully described in the subjoined specification and particularly pointed out in the following claims.

Figure 1 is a top plan view, centrally broken out, of a portion of an automatic filling-replenishing loom with one form of 90 my present invention embodied therein, the mechanism being set for operation in accordance with the provisions of case A, above referred to; Fig. 2 is a front elevation, centrally broken out, of a portion of the apparatus shown in Fig. 1, showing the connections between the two filling-detectors and the connection between the replenishing mechanism and the feeler and the main or left-hand detector; Fig. 3 is an enlarged 95 transverse sectional detail on the line 3-3, Fig. 1, looking toward the right; Fig. 4 is a similar view, but omitting some of the parts shown in Fig. 3, and with the controlling or governing member changed in position to 100 change the operation of the loom to that specified in cases C or D. Fig. 5 is a perspective view of the controlling or governing member, detached.

110 The lay A³ having shuttle-boxes B, B^X,

the automatically self-threading shuttle S^X , the filling-replenishing mechanism, including the transferer F' and filling-feeder F (partly shown) the controlling rock-shaft d' for said 5 replenishing mechanism, shipper S , notched holding-plate N therefor, and a releasing device or knock-off lever N^X for the shipper, may be and are all of well known construction and operate in usual manner, the inner 10 end of lever N^X having an enlargement n .

The main filling-detector is located at the shipping side of the loom, and the auxiliary filling-detector at the replenishing side, the auxiliary detector including a filling-fork g 15 and its slide g^X , longitudinally movable in the fixed guide g^2 , the fork-tail being engaged by the hook w^X of an actuator or weft-hammer W^X , Fig. 1, when the fork is not tilted, to thereby move the slide outward against its 20 spring s^X . Such movement of the slide swings outward an arm 2 having its hub 3 loosely mounted on the rock-shaft d' , see Fig. 2, the inner end of the hub having a projection or lug 4 thereon which enters a notch 25 5 in a tubular shaft or sleeve 6, herein shown as loosely mounted on and supported by the rock-shaft d' .

The coupling or connection between the arm 2 and the shaft or sleeve 6 causes the 30 latter to be turned in the direction of arrow 300, Fig. 4, when the slide g^X is moved outward, as will be manifest, and as will be explained hereinafter take-up is arrested thereby.

The cam for actuating the right-hand weft-hammer, in the Northrop patent referred to, was given a peculiar shape in order to prevent an extra replenishment of filling by or through the right-hand fork detecting 35 filling absence immediately after the feeler had operated, and the somewhat quick, jerky motion of the weft-hammer due to the shape of the cam in practice has a tendency at times to effect an unsatisfactory action of 40 the mechanism. In my present invention I obviate the use of this irregularly shaped cam, as explained hereinafter, for the fork g is connected only with the sleeve 6, and not in any way with the controlling rock-shaft 45 d' , and consequently I obviate the quick, jerky motion of the weft-hammer.

In the Northrop patent the shape of the cam referred to is necessary in order to afford time enough to stop the loom in case 50 the filling runs out on the same pick on which the feeler detected.

By my present construction, connecting the auxiliary fork mechanism with a rocking member, as the sleeve 6, and using a separate 55 rocking member, as the rock-shaft d' in connection with the feeler, (as will be made clear hereinafter) it is unnecessary to provide means acting through the same agency, viz: rock-shaft d' , whereby the right-hand fork and the 60 feeler may perform different functions.

Returning to Fig. 1; the main filling-detector includes the fork f mounted on slide f^X , moved outward in a guide f^2 by the weft-hammer W when its hook w engages the fork-tail, the outward movement of the slide against its spring s causing its shoulder f^3 to engage a lateral extension 7 on the upper end of an arm 8, herein shown as having its hub 9 loosely mounted on the rock-shaft d' . Said hub 9 has on its inner end a lug 10, 70 Fig. 2, to enter a notch 11 in the adjacent end of the tubular shaft or sleeve 6 thereby coupling the latter and the arm to move in unison.

The arm 8 has secured to it a depending, 80 rearwardly-projecting extension d^2 , Fig. 4, adapted when elevated to cause the arrest of the take-up mechanism (not shown) in substantially the manner described in United States patent to Northrop No. 789,291, 85 dated May 9, 1905. That is, a lug d^3 on the extension may engage the pawl-carrier p^X and move the same to disengage the pawl from the ratchet in take-up mechanism of suitable character, such for instance as is 90 shown in United States Patent No. 643,284.

From the foregoing it will be obvious that detection of filling absence by either detector f , or g , will operate to turn the connection 6 between the arms 2 and 8 in the direction of 95 the arrow 300, Fig. 4, to thereby elevate the extension d^2 and arrest take-up, but it will be manifest that no operation of the rock-shaft d' to replenish filling can be effected merely by such turning of the connection 6, for the latter is not in any way coupled with the rock-shaft d' .

As best shown in Figs. 3 and 4 the upper end of the arm 8 is shaped to present an out-turned hook 12, for a purpose to be described, and the fork-slide f^X has on its outer side a boss 13 reduced in diameter to present a horizontal stud 14, adapted to receive a removable fastening, such as a cotter-pin 15, Fig. 1, the boss being shown adjacent the shoulder f^3 on the slide.

The filling-exhaustion indicating mechanism herein shown, see Fig. 1, comprehends a stand 9 X on the holding-plate N , supporting a yieldingly-controlled slide 12 X having at its front end a shank 14 X , ears 18 X on the slide sustaining the bunter 21 X and the actuator 26 X , co-operating with the shank of the feeler proper 28 X , all substantially as in the Northrop Patent No. 833,796, hereinbefore 115 referred to and operating as therein provided. The tilting transmitter 34 X fulcrumed at 33 X has its outer end bent at 37 X and provided with a cam slot (not shown) through which extends the controller 40 X , the inner 120 end of the transmitter projecting loosely into a longitudinal slot 16, Fig. 3, in the rear end of the latch d^3X pivotally connected at its front end on the bifurcated upper end of an arm d^2X fast on the rock-shaft d' . The 125 130

- actuator 26^x will not coöperate with the controller 40^x until the filling in the running shuttle is exhausted to a predetermined extent, which is indicated by the feeler 28^x as it intermittently engages the filling in the shuttle, in well-known manner, and up to the time of predetermined exhaustion the transmitter 34^x is quiescent, and the latch d^{3x} maintains the position shown in Fig. 3.
- 10 When the predetermined filling exhaustion is attained the actuator engages and moves the controller 40^x to tilt the transmitter, elevating the rear end of the latch d^{3x} into the path of the head w^x on the weft-hammer W, and on the forward stroke of the latter the latch is pushed forward, acting through arm d^{2x} to turn the controlling rock-shaft d' in the direction of arrow 300, Fig. 4. Filling replenishment is thereafter effected when the 20 shuttle reaches the replenishing shuttle-box B^x, Fig. 1. Inasmuch as the arm d^{2x} is fast on the rock-shaft d' and has no connection with the sleeve 6 it will be manifest that filling replenishment by or through the filling-exhaustion indicating mechanism is not accompanied by arrest of take-up, and this is as it should be, for as there is no break in the continuity of the filling being laid there is no occasion for arrest of take-up.
- 25 30 So far as the construction has been explained it will appear that neither of the filling-detectors can upon detection of filling absence, effect a change or replenishment of filling, but I have provided simple means whereby such replenishment can be effected by the main or left-hand fork f when desired, as for instance in cases A and B.
- The operation of the loom is varied, in changing from cases A and B to cases C and 35 D, or vice versa, by a controlling or governing member or device, shown separately in Fig. 5, and consisting of an elongated flat body 17 having a longitudinal slot 18 and at its front end a rigid lug 19 is extended laterally from one side of the body, the latter in use standing on edge, as in Fig. 1, 3 and 4. At its rear end the body is enlarged at 20 and shaped to present at one edge a shoulder 21, and on the opposite edge a shouldered lug 22, the shoulder 21 being nearer the front end of the body than is the lug 22. The edges of the enlargement 20 adjacent the shoulder and lug are flattened at 21^x, 22^x, respectively, and parallel to the adjacent edges of the body.
- 40 45 50 55 The controller is located between the latch d^{3x} and the adjacent side of the guide f² for the main fork-slide, the stud 14 on said slide entering the slot 18 and normally lying therein at the front end of the slot, Figs. 3 and 4.
- 60 65 When the loom is to be run in accordance with cases A and B the controller is so mounted that its lug 19 will extend to the left, Figs. 1 and 3, behind the upraised side 23 of the bifurcated arm d^{2x}, with the lug 22 down-turned, the edge 22^x then resting on the at-
- taching ear f⁶ of the guide f². A retainer, such as a cotter-pin 15, in the stud 14, retains the controller thereon.
- When the feeler operates and the latch d^{3x} is pushed forward as explained it effects filling replenishment but has no influence over the controller, as its lug 19 has no engagement with the latch. If, however, the filling breaks and its absence is detected by the main fork f, the slide f² thereof will be moved outward by the usual coöperation with the weft-hammer W, and the stud 14 on the slide will draw forward with it the controller, and the lug 19, engaging the part 23 of the arm d^{2x}, will swing the latter outward, 70 turning the rock-shaft d' to effect filling replenishment when the shuttle is in the shuttle-box B^x. At the same time the slide shoulder f³ engages the lateral extension 7 of arm 8 and swings the latter outward, 75 acting through the extension d² to arrest take-up. If the main detector f does not detect filling absence first, but such absence is detected by the auxiliary detector g on the pick of the shuttle to box B^x, then the slide 80 g² is moved outward by its weft-hammer g^x, the arm 2 is swung outward and the sleeve connection 6 is turned. Such turning of said connection turns with it the hub 9 and arm 8, and thereby take-up will be arrested, but there will be no movement whatever imparted to the main fork-slide f² nor to the rock-shaft d', as there is no connection with the arm 8. Hence there is no actuation 85 of the replenishing mechanism, either directly or indirectly, by or through the auxiliary detector, its sole function being to arrest take-up when it detects filling absence, and to effect loom stoppage at such time in cases 90 C and D.
- 95 100 105 When the loom is operating as in case A and the filling breaks or runs out on the flight of the shuttle to the replenishing box B^x, after the feeler mechanism has operated, the auxiliary detector g will detect such failure of the filling and will arrest take-up, but there will be no second operation of the replenishing mechanism, as will be obvious, said detector g having no operative connection with the controlling rock-shaft d', and 110 unnecessary denudation of the filling-feeder is obviated without the use of special means to prevent such denudation, as in the Northrop patent referred to.
- 115 120 Referring to Fig. 3 it will be seen that while the enlargement or shelf n of the knock-off lever is in the path of the lug 22 of the controller said lug is so far back that forward movement of the controller by the main fork-slide f² is insufficient to bring the shoulder of the lug into coöperative engagement with the shelf, to effect loom stoppage.
- 125 130 From the foregoing description it will be seen that when the controlling member 17 is set as in Figs. 1 and 3 either the filling-ex-

haustion indicating mechanism or the main filling-detector will effect filling-replenishment, and that take-up is arrested when either the main or the auxiliary detector detects filling absence, thus fulfilling the conditions of case A.

To change from case A to case B, that is, with the filling-exhaustion indicating mechanism out of action, but with filling replenishment effected automatically by or through detection of filling absence by the main detector, the filling-exhaustion indicating mechanism is conveniently maintained out of action by pushing forward the feeler until a hole 100 (see dotted lines Fig. 1) in its shank 14^X is exposed, and a suitable pin is inserted in the hole, maintaining the feeler device retracted and inoperative.

In case A and case B there is no great objection to an occasional pick in which the filling is more or less incomplete, but in certain classes of goods, such incomplete picks must not be present, and when the loom is to weave such goods provision must be made for automatic stoppage whenever the filling fails, whatever be the cause, replenishing of filling being effected solely through the filling exhaustion indicating mechanism. When so operating the loom conforms to the conditions of case C, and this requires a change in the position of the controller or governing member, with a subsequent change in its mode of operation.

To change over to case C the retaining device 15 is withdrawn, the controller is disengaged from one stud 14 and reversed or turned upside down from its position in Fig. 3 to that shown in Fig. 4, and it is then replaced on the stud 14 and the retainer 15 applied. By such reversal the lug 19 will project to the right of the controller, and immediately in front of the hooked upper end 12 of the arm 8, as shown in Fig. 4, the shoulder 21 now being downturned and the adjacent edge 21^X rests upon the ear f^o.

It will be seen that the shoulder 21 is very near the shelf n of the knock-off lever N^X, and that very slight forward movement of the controller will act through said shoulder 21 to operate the lever N^X and effect release of the shipper.

Filling replenishment by or through the feeler device is now effected in usual manner, when predetermined filling exhaustion is attained, the latch d^{sX} being omitted in Fig. 4 in order to show clearly parts which would otherwise be hidden. If the filling fails and its absence is detected by the main detector f the slide f^X will be moved outward, acting through the extension 7 to rock the arm 8 and arrest take-up, and at the same time the controller is moved outward, the shoulder 21 acting against the shelf n and causing the knock-off lever N^X to release the shipper 65 from its holding notch to stop the loom. If

the auxiliary detector g detects filling absence its slide g^X is moved outward, rocking the arm 2 and turning the sleeve 6 in the direction of arrow 300, Fig. 4, thereby swinging outward the upper, hooked end 12 of the arm 8. As the lug 19 on the controller is in front of said hooked end 12 the controller is moved forward and the shipper is released, to stop the loom, while take-up is also arrested.

It will be seen that when the controller is moved forward by or through detection of filling absence by the detector or fork g the slot 18 prevents any movement of the main fork-slide f^X, to retract the fork from detecting position, as the controller is moved forward relatively to the stud 14, which traverses the slot. The controller is thus the connecting member between the knock-off lever N^X and either fork-slide when set as in Fig. 4, whereas when set as in Fig. 3 the controller becomes the connecting member between the main fork-slide only and the rock-shaft d' which governs filling replenishment.

When the controller is set as in Fig. 3, its rear end cannot jump up accidentally because the upper end of the arm d^{sX} prevents any descent of the lug 19.

When the controller is set as in Fig. 4 the hooked end 12 of arm 8 cooperates with the lug 19 and prevents its descent.

If the loom is operating under the provisions of case C and the feeler has operated to effect filling replenishment, suppose that the filling breaks or runs out on the pick of the shuttle to the replenishing side of the loom. Under such conditions the auxiliary detector g detects the filling absence and its slide moves forward, thereby acting through arm 2, sleeve 6 and arm 8 to move the controller 17 forward to operate the knock-off lever N^X, stopping the loom and arresting take-up. This prevents the continued operation of the loom after replenishment with a pick having only a partial filling laid therein, with the simple mechanism herein shown, obviating the peculiar structure present in the Northrop Patent No. 833796 to effect a similar result.

To change the loom from operating as in case C to operate as in case D the filling-exhaustion indicating mechanism is withheld from operation by retracting the feeler, as in case B. The loom will then run simply as a double-fork loom, breakage or running out of the filling arresting take-up and causing stoppage of the loom. In either case B or case D, the feeler being held retracted and inoperative, the transmitter 34^X will be in normal position, with the rear end of the latch d^{sX} out of the path of the head w^X of the weft-hammer W.

Various double-detector loom structures have heretofore been devised in which either detector operated to effect filling replenish-

ment, and in such structures it has been necessary to provide some means to prevent the detector or fork at the replenishing side of the loom from effecting replenishment when the shuttle is boxed at the opposite side of the loom. Different instrumentalities have been used for this purpose, including a lost-motion connection between the right-hand detector and the controlling rock-shaft; a smaller cam for the weft-hammer at the replenishing side of the loom, and the mechanism shown in patent to Stafford No. 805,497 dated November 28, 1905. None of these devices are necessary in connection with my present invention, because, as has been explained, it is impossible under any circumstances for the detector or fork at the replenishing side of the loom to initiate a replenishment of filling.

20 I have herein shown one practical embodiment of my invention, and it will be manifest that various changes or modifications in different details of construction and arrangement may be made by those skilled in the art 25 without departing from the spirit and scope of my invention.

Having fully described my invention, what I claim as new and desire to secure by Letters Patent is:—

30 1. In a loom provided with filling-replenishing mechanism, and with means to cause the operation thereof prior to complete exhaustion of the running filling, in combination, two detectors to detect filling absence 35 on alternate picks, a stopping instrumentality for the loom, and governing means, including a member manually changeable as to its position, to operatively connect the stopping instrumentality with both detectors, or 40 to operatively connect the replenishing mechanism with one only of the detectors, according to the position of said member.

2. In a loom provided with filling-replenishing mechanism, and with means to cause the operation thereof prior to complete exhaustion of the running filling, in combination, two detectors to detect filling absence 45 on alternate picks, and adapted to arrest the operation of a take-up instrumentality upon detection of filling absence by either detector, and governing means, including a member manually changeable as to its position, to operatively connect the replenishing mechanism at will with one only of the detectors, according to the position of said member.

3. In a loom provided with filling-replenishing mechanism, and a stopping instrumentality, in combination, two detectors to detect filling absence on alternate picks and adapted to arrest the operation of a take-up instrumentality upon detection of filling absence by either detector, and governing means, including a member manually changeable as to its position, to operatively connect

the stopping instrumentality with both detectors, or to operatively connect the replenishing mechanism with one only of the detectors, according to the position of said member.

4. In a loom provided with filling-replenishing mechanism, and a rock-shaft to control the time of its operation, in combination, two instrumentalities to detect filling absence on alternate picks, a take-up arresting member operatively connected with both instrumentalities, whereby filling absence detected by either will arrest take-up, and manually controlled means to at will operatively connect one only of said detecting instrumentalities with the rock-shaft, to effect filling replenishment by or through detection of filling absence by the operatively connected instrumentality.

5. The combination, in a loom provided with filling replenishing mechanism, of two filling-detecting instrumentalities located at opposite sides of the loom, a take-up arresting member permanently and operatively connected with both instrumentalities, to effect arrest of take-up upon detection of filling absence by either instrumentality, and manually changeable means whereby one only of said instrumentalities may be operatively connected with or disconnected from the filling replenishing mechanism.

6. The combination, in a loom provided with filling replenishing mechanism, of two filling-detecting instrumentalities located at opposite sides of the loom, and each adapted, upon detection of filling absence, to effect the arrest of a take-up instrumentality, and manually controllable means whereby at will one only of said detecting instrumentalities may, upon detection of filling absence, effect the actuation of the replenishing mechanism.

7. The combination, in a loom, of mechanism to cause filling replenishing prior to complete exhaustion of the running filling, a stopping instrumentality, two filling-detectors to detect filling absence on alternate picks, slides on which the detectors are mounted, a governing device adapted when actuated to effect the operation of the stopping instrumentality, a slot and pin connection between said device and one of the slides, and a separate connection between the other slide and the governing device, operative movement of either slide upon detection of filling absence by its detector acting immediately to actuate the governing device, the slot and pin connection between the latter and one slide permitting such slide to remain quiescent when the other slide actuates the governing device.

8. The combination, in a loom having mechanism to cause filling replenishment prior to complete exhaustion of the running filling, a shipper, and a releasing device therefor, of two filling-forks and their slides, located at opposite sides of the loom, a slot-

ted governing member having a shoulder to engage and operate the shipper-releasing device, a stud on one slide to enter the slot and actuate the governing member when the corresponding fork detects filling absence, and a separate connection between the governing device and the other slide, to actuate the former when filling absence is detected by the fork on such slide, the slot in the governing member at such time permitting its actuation while the stud-carrying slide remains quiescent.

9. The combination, in a loom provided with filling-replenishing mechanism and with a rock-shaft to control the time of operation of said mechanism, of a shipper, a releasing device therefor, two filling-forks to detect filling absence on alternate picks, a governing member manually changeable as to its position, to operatively connect one only of the filling-forks with said rock-shaft, when in one position, to thereby effect filling replenishment upon detection of filling absence by said fork, and when in another position to cooperate with the shipper-releasing device, and separate operating connections between the governing member, when in the latter position, and both filling-forks, whereby detection of filling absence by either fork will cause the governing member to operate the shipper-releasing device.

10. In a loom provided with filling-replenishing mechanism, and with means to cause the operation thereof prior to complete exhaustion of the running filling, in combination, two filling-detectors to detect filling-absence on alternate picks, a device adapted to arrest the operation of a take-up instrumentality and actuated upon detection of filling-absence by either detector, a stopping instrumentality for the loom, and means, including a manually reversible controlling member to effect the operation of the replenishing mechanism by or through detecting action of one detector only, or of the stopping instrumentality by or through detecting action of either detector, according to the position of said controlling member.

11. In a loom, provided with filling-replenishing mechanism, and with means to cause the operation thereof prior to complete exhaustion of the running filling, in combination, two filling-detectors to detect filling absence on alternate picks, and adapted to arrest the operation of a take-up instrumentality, upon detection of filling-absence by either detector, and means including a manually reversible controller to effect the operation of the replenishing mechanism by or through detecting action of one only of said detectors, or the operation of the stopping instrumentality by or through detecting action of either detector, in accordance with the position of the controller.

12. In a loom provided with mechanism to

furnish fresh filling prior to complete exhaustion of the running filling, two filling-detectors to detect filling-absence on alternate picks and adapted to arrest the operation of a take-up instrumentality when filling-absence is detected by either detector, a stopping instrumentality for the loom, connections between the stopping instrumentality and the detectors and between one only of the detectors and the replenishing mechanism, and a manually set controller adapted to form a part of either of said connections, whereby filling-replenishment will be effected upon detecting action of one only of said detectors or loom-stoppage will be effected upon detecting action of either detector, according to the setting of said controller.

13. In a loom, in combination, filling-replenishing mechanism, means to cause the operation thereof prior to complete exhaustion of the running filling, filling-detectors at opposite sides of the loom, a shipper, a releasing device therefor, a rock-shaft operatively connected with the replenishing mechanism, a device to arrest the operation of a take-up instrumentality upon detection of filling absence by either detector, a manually reversible controller having a shoulder, separate operating connections between the controller, when in one position, and the filling-detectors, to operate the releasing device by the shoulder of the controller, when filling absence is detected by either detector, and independent means operating through the controller when in reversed position to turn the rock-shaft and effect filling-replenishment upon detection of filling absence by one only of the detectors.

14. In a loom provided with filling-replenishing mechanism and with a controlling rock-shaft therefor, in combination, means to turn said shaft and effect filling replenishment upon substantial exhaustion of the filling in the running shuttle, two filling-detectors at opposite sides of the loom, means, including a manually reversible controller to turn said rock-shaft by or through detection of filling-absence by one only of the detectors, a take-up arresting device operated by detection of filling-absence by either detector, a stopping instrumentality for the loom, a shoulder on the controller, inoperative when the latter is set to turn the rock-shaft, reversal of the controller positioning the shoulder to actuate the stopping instrumentality by bodily movement of the controller, and separate connections between the controller when so reversed and the two filling-detectors, to effect bodily movement of the controller by or through detection of filling absence by either detector, said controller when thus reversed having no control over the rock-shaft.

15. In a loom, provided with filling-replenishing mechanism, and means to cause

the operation thereof, prior to complete exhaustion of the filling in the running shuttle, in combination, means to detect filling absence on every pick, a stopping instrumentality for the loom, and means to at will cause the operation of either the replenishing mechanism on detection of filling absence on the pick of the shuttle in one direction only, or of the stopping instrumentality on detection of filling absence on a pick of the shuttle in either direction.

16. In a loom, in combination, means to cause filling replenishment prior to complete exhaustion of the filling in the running shuttle and adapted to be maintained inoperative at will, separate means to either cause filling replenishment upon filling absence on the pick of the shuttle in one direction only or to stop the loom upon filling absence on a pick of the shuttle in either direction, and a reversible, manually set controller to determine by its position when set whether said second-named means shall cause filling replenishment or loom stoppage, irrespective of the operation or non-operation of the first-named means.

17. In a loom provided with filling-replenishing mechanism, in combination, means, including a latch and a rocking arm with which it is connected, to effect the operation of said mechanism prior to complete exhaustion of the running filling, a vibrating weft-hammer to at times coöperate with the latch and rock said arm, main and auxiliary filling-forks each having a slide and adapted to detect filling absence on alternate picks and also adapted to arrest the operation of a take-up instrumentality upon detecting action of either fork, a shipper, a releasing device therefor, a manually reversible controller having a shoulder and a lateral lug, a slot and pin connection between the controller and the main fork-slide, the lug of the controller when in one position engaging the rocking arm and actuating the same upon outward movement of the main slide, to effect filling replenishment by or through detection of filling absence by the main fork, reversal of the controller causing its shoulder to operate the shipper-releasing device upon detection of filling absence by either fork, the lug of the controller when reversed being out of engagement with the rocking arm, and an operative connection between the auxiliary fork-slide and the controller lug when the controller is reversed, to operate the shipper-releasing device through the controller by filling absence detection by the auxiliary fork, the slot and pin connection between the controller and main slide at such time permitting said slide to remain quiescent.

18. In a loom provided with filling-replenishing mechanism, a controlling rock-shaft

therefor, having an attached arm, a sleeve 65 loose on the rock-shaft and having attached arms, main and auxiliary filling-forks and a slide for each, outward movement of either slide acting through one of the arms on the sleeve to rock the latter, and a take-up arm 70 resting device operated by such a rocking movement, combined with a shipper, a releasing device therefor, a manually reversible, longitudinally-slotted controller having a shoulder at its rear end and a lateral lug 75 at its front end, and a stud on the main slide to enter the slot and actuate the controller by outward movement of said slide when the main fork detects filling absence, the controller-lug coöperating with the arm on the 80 rock-shaft to turn it and effect filling replenishment by outward movement of the main slide, when the controller is in one position, said lug, when the controller is in reverse position, extending in front of the arm 85 on the sleeve adjacent the main slide while the shoulder coöperates with the shipper-releasing device, whereby outward movement of the auxiliary fork-slide rocks the sleeve and through said arm moves the controller to operate the releasing device, outward movement of the main slide acting through its stud directly upon the controller when so reversed to operate the releasing device.

19. In a loom, mechanism to cause filling replenishment prior to complete exhaustion of the running filling, means to detect filling absence on alternate picks, a stopping instrumentality and a manually set controller 100 to operatively connect, independently of the replenishing mechanism, the stopping instrumentality and the detecting means, to stop the loom upon detection of filling absence, or to operatively connect the replenishing mechanism and the detecting means, to cause filling replenishment upon detection of filling absence on a predetermined pick.

20. In a loom, mechanism to cause filling replenishment prior to complete exhaustion 110 of the running filling, detectors to detect filling absence at both sides of the loom, means independent of said mechanism to effect arrest of take-up on detection of filling absence, and devices by which detection of 115 filling absence may be made to cause either replenishment of filling or loom stoppage at will.

21. In a loom, mechanism, including a rock-shaft, to cause filling replenishment, 120 take-up arresting means, a stopping instrumentality, filling-forks at opposite sides of the loom to operate said take-up arresting means upon detection of filling absence by the forks, and a controller to operatively 125 connect a filling-fork either with said rock-shaft or with the stopping instrumentality, at will.

22. In a loom, mechanism to cause filling replenishment, said mechanism including a member to govern the time of its operation, a stopping instrumentality, filling-forks at 5 opposite sides of the loom, means to arrest take-up upon detection of filling absence by either fork, and a controller to at will operatively connect one only of the forks with the governing member of the replenishing mechanism or to effect operation of the stopping 10

instrumentality by or through detection of filling absence by either fork.

In testimony whereof, I have signed my name to this specification in the presence of two subscribing witnesses.

CLARE H. DRAPER.
